Attest,

United States Patent Office.

PETER RICHMOND, OF ABERDEEN, AND ABNER McFARLAND, OF ALLENSVILLE, INDIANA.

Letters Patent No. 78,131, dated May 19, 1868.

IMPROVED BOOT-CRIMPER.

The Schedule referred to in these Letters Patent and making part of the same.

TO ALL WHOM IT MAY CONCERN:

Be it known that we, PETER RICHMOND, of Aberdeen, in the county of Ohio, and ABNER McFARLAND, of Allensville, in the county of Switzerland, and in the State of Indiana, have invented certain new and useful Improvements in Boot-Crimpers; and do hereby declare that the following is a full, clear, and exact description thereof, reference being had to the accompanying drawings, and the letters of reference marked thereon. In the annexed drawings, making a part of this specification—

A represents a suitable frame or table, to which are pivoted or hinged jaws B B, and provided with a slot in one end, in which is pivoted an eccentric, D.

B B represent jaws of any suitable size, pivoted in or hinged to the top of the table A, in any manner desired, the tops thereof bevelled off nearly to a point in the middle, as shown in the drawings.

Passing through the said jaws B B is a bolt, g, which has an eccentric, C, pivoted to one end thereof, and a nut, h, at the other. The nut h is for the purpose of regulating the distance between the jaws B B to suit the difference in the thickness of leather or material to be crimped, and also to correspond with different sizes and thickness of the crimping-form or board F.

D represents an eccentric-lever, which is pivoted to the table A, and works in the slot thereof, and operates the eccentric, C, by means of the rod l, which is pivoted to both the eccentrics, C and D. The eccentric, D, is also attached to a horizontal lever, E, by means of the rod or loop S, and operates said lever up and down, as may be required.

E represents a long horizontal lever, pivoted at one end of the table A, and extending the whole length thereof, and beneath it, as shown.

Pivoted to said lever E, and extending upward through a slot in the table A, is a double or forked hook, j, for the purpose of catching over the crimping-form F, and by means of the eccentric-lever D, and the horizontal lever E, pulling the same down between the jaws B B, and thereby crimping and giving form to the leather of the front of a boot, by one simple motion by the operator.

The eccentric, C, is for the purpose of pressing the jaws firmly against the crimping-form F, or the leather thereon, at the same time it is being brought down by the hook j.

By adjusting the leather, cut in the required shape, in any convenient manner, to the crimping-form F, and placing the same in or against the mouth or upper ends of the jaws B B, and then attaching the hook j, above or over the said form F, the whole operation of crimping, after being so adjusted, is almost instantaneous, and is done with one motion of the hand of the operator, by means of the eccentric-lever D.

The crimping-form F is constructed in any of the ordinary forms and ways most in use. Any old form may be used with this device, without any alteration whatever.

Having thus fully described our invention, what we claim as new, and desire to secure by Letters Patent, is—
1. The lever E, in combination with the hook j, when constructed, used, and operated substantially as and for the purpose set forth.

2. The arrangement of the jaws B B, bolt g, eccentrics, C and D, lever E, and forked rod j, the several parts being constructed and operated substantially as and for the purpose specified.

In testimony that we claim the foregoing, we have hereunto set our hands, this 8th day of January, 1868.

PETER RICHMOND,
ABNER McFARLAND.
